COMPARTMENT COMB

William J. Martino, Garden City, Mich.

Application March 12, 1947, Serial No. 734,026

1 Claim. (Cl. 132—79)

1

The present invention relates to a compartment comb having a receptacle particularly adapted to contain hairpins or other small articles, including manicuring implements or cosmetic containers.

Among the primary objects of the present invention are to provide an improved compartment comb of simplified and economical construction wherein the compartment is readily and conveniently accessible by means of an improved removable cover therefor.

Another object is to provide an improved compartment comb of the character described wherein in the cover retaining mechanism is particularly adapted to avoid entangling the hair during combing, and wherein the receptacle and cover are cooperable with the comb in providing a comb of ornamental and modern design.

Other objects are to provide an improved compartment comb having a detachable cover which may be readily secured in interlocking engagement with the comb in cover position over the receptacle, or detached therefrom, by a simple sliding movement; and to provide such a compartment comb having a slidable cover of resilient material which also may be readily sprung into locked cover position.

Another object is to provide a compartment comb having an improved hinged access to the compartment in the back thereof, wherein the back portion of the comb is split longitudinally essentially along the midline of the back and for the length of the compartment therein, and one half of the split back portion is hinged at its ends to provide a compartment opening similar to the hinged top opening of a lady's handbag.

Other objects of this invention will appear in the following description and appended claim, reference being had to the accompanying drawings forming a part of this specification wherein like reference characters designate corresponding parts in the several views.

In the drawings:

Fig. 1 is a side view of a compartment comb embodying the present invention, a portion of one cover member being broken away.

Fig. 2 is an enlarged section taken in the direction of the arrows essentially along the line 2—2 of Fig. 1.

Fig. 3 is an enlarged fragmentary isometric view of the compartment cover shown in Fig. 1, showing the chamfered ends of the depending flanges of the cover.

Fig. 4 is a side view of another embodiment of a compartment comb employing the present invention.

2

Fig. 5 is an enlarged fragmentary section taken in the direction of the arrows essentially along the line 5—5 of Fig. 4.

Fig. 6 is a fragmentary side view of another embodiment of a compartment comb employing the present invention.

Fig. 7 is an enlarged fragmentary end view taken in the direction of the arrows essentially along the line 7—7 of Fig. 6.

Fig. 8 is a fragmentary cross section through the back portion of still another compartment comb embodying the present invention, a fragmentary portion of the hinged compartment cover being shown in the open position in phantom.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Briefly the present invention proposes an improved compartment comb wherein a longitudinally grooved compartment or receptacle is formed in the back or body portion of the comb. The compartment may extend the entire length of the comb body, or any portion thereof, and may comprise one continuous compartment, or a plurality of separate compartments, permitting the owner of the comb to conveniently carry a number of small articles in separate compartments. The various advantages of the type of compartment comb disclosed herein may be readily achieved in a number of forms, with various means being employed to hold the compartment covers in position, without departing from the spirit of my invention. Several such embodiments of my invention are described in detail below by way of example.

Referring to Figs. 1, 2 and 3, one such embodiment of a compartment comb employing the present invention is shown wherein the back or body portion 10 of the comb provides the two symmetrically disposed grooved receptacles or compartments 11. In the example shown, each of the two compartments 11 opens from one of the two sides 12 of the back 10, and the two compartments 11 are situated at opposite ends of the comb body 10. The compartments 11 may also open to the back face 13 of the comb body 10, or to portions of both the sides 12 and back 13 where desirable. The compartments 11 are primarily

adapted for receiving hairpins or bobby pins or similar small articles, although the compartments 11 may be adapted in various sizes or lengths for various purposes. By slightly enlarging the body portion 10, the compartments 11 may be adapted for receiving small cosmetic containers or manicuring implements.

On either longitudinal side of each compartment 11 and parallel thereto are the longitudinal cover receiving channels 14, which are preferably undercut toward the grooved receptacles 11 at the base of the channels 14 as shown in Fig. 2. The covers 15 for the receptacles 11 each provide a pair of longitudinal depending flanges or runners 16 which are slightly inturned so as to engage and interlock with the undercut channels 14. As shown in Fig. 3, the ends 17 of the runners 16 are chamfered to serve as inclined surfaces to raise the ends of the runners 16 from their corresponding channels 14, and to facilitate slidable removal of the covers 15 from their corresponding compartments 11. Thus each cover 15 may be readily slid longitudinally from its cover position merely by pushing longitudinally on the upper surface thereof. If desired, the ends of the channels 14 may also be inclined to provide inclined planes to cooperate with the chamfered ends 17. It is also possible to incline only the ends of the channels 14 and not the runner ends 17. However, the construction shown in Fig. 3 wherein only the ends 17 of the runners 16 are inclined is satisfactory for purposes of illustration.

With the exception of the compartment assembly, the comb shown may be conventional in other respects and may be formed in the manner of conventional combs, as by molding from hard rubber or suitable plastic material for example. The cover 15 may be similarly molded. Accordingly the sliding cover arrangement permits economies in the manufacture of the comb inasmuch as the compartments 11 and channels 14 may be molded into the comb body 10 during the molding of the comb without the expense of additional forming or assembling operations. Thus the arrangement of the detachable sliding cover 15 as shown offers practically no problem in assembly, such as the fastening of hinges required for the hinge type cover, or the addition of locking means to hold the covers in cover position.

Also by the arrangement shown, the covers 15 may be adapted to lie flush with the side 12 of the comb. The mechanism for holding the cover 15 in place is both concealed and unobtrusive so as to avoid entangling the hair during combing, and interference with the ornamental features of the comb. Furthermore, the detachable covers 15 readily permit the utilization of various decorative colors which may differ from the color of the comb body 10.

The covers 15 are preferably formed of resilient material so that they may be attached to the comb body 10 in cover position merely by springing the edges of the runners 16 apart and forcing them into the channels 14. In this respect the runners 16 may be interlocked with the channels 14 without sliding the runners 16 into the channels 14 from the ends thereof.

Referring to Figs. 4 and 5, another embodiment of the present invention is shown wherein the comb 18 has the longitudinal sliding channel cover 19. In this example the longitudinal grooved compartment 20 opens to the back face of the comb 18. On either side of the compartment 20 are the longitudinal bead moldings 21 which extend essentially the length of the back

of the comb 18 so as to engage the inturned clips 22 which comprise the channel sides of the channel cover 19, Fig. 5.

Both the bead moldings 21 and the side clips 22 extend longitudinally essentially the length of the compartment 20, which extends essentially the length of the comb 18. It is apparent that the compartment 20 may be separated into a number of smaller compartments similar in size to the compartments 11 of Fig. 1. Also the bead moldings 21 and the side clips 22 need not be continuous along the entire length of the compartment 20, and for certain purposes may comprise a number of short sections adapted to interlock essentially as shown, Fig. 5.

The cover 19 may be removed from the comb by sliding off one end or the other. Where desirable, the ends 23 of the comb 18 may be slightly enlarged to prevent accidental displacement of the cover 19. In such a case, the inherent resiliency of the channel cover 19 must be sufficient to permit spreading of the channel sides 22 upon the application of a light force so as to allow the cover 19 to slide on or off an end of the comb 18.

It is to be noted that in opening either the compartments 11 or the compartment 20, the corresponding slide covers 15 or 19 need not be completely detached from their respective comb bodies. Accordingly where a number of small items or articles are contained within the compartment, the sliding type of cover has the advantage of permitting the compartment to be opened gradually, or to a small extent at one end, to safeguard against losing its contents.

Figs. 6 and 7 show still another embodiment of a compartment comb employing my invention. In this instance the cover 24 is hinged to the comb body 25 by means of the pivot pins 26 which are embedded in the cover 24 at opposite ends thereof and into the adjacent bosses 27. The two bosses 27 project from the comb body 25 at opposite ends of the hinged cover 24 as shown in Fig. 6. The compartment 28 in this example opens from one side of the comb body, although where desired for other types of compartment combs having hinged covers, the compartment 28 may open to other portions of the comb body.

Such an example is shown in Fig. 8, which is a cross sectional view essentially through the back portion of another hinged cover compartment comb embodying the present invention. The compartment 29 opens to one side and to the back of the comb body 30. The back face 31 of the comb body 30 is split essentially along its midline for the length of the compartment 29, so that the cover 32 closes along the midline of the back face 31 similarly to the closing of a lady's pocketbook. The cover 32 is hinged at opposite ends to the comb body 30 by pins 33, thereby avoiding objectionable protuberances and also permitting the cover 32 to lie flush with the adjacent portions of the body 30. Thus the compartment cover inconspicuously blends with the styling of the comb and avoids projecting hinges or other protuberances which might entangle the hair during combing.

Both of the hinged covers 24 and 32 may be locked in the closed position by any one of numerous conventional fastening means similar to those conventionally employed with cigarette cases, lady's pocketbooks, or compacts, for example.

By the above specification and description I have disclosed a novel and convenient compartment comb of economical manufacture, which permits a built-in compartment that does not in-

terfere with the ornamentation of the comb or employ exposed mechanisms which might entangle the hair, and which is adapted for use with either a hinged type compartment cover or a 5 slidable compartment cover interlockable with the comb body.

I claim:

In a compartment comb, the combination of a body portion having a compartment therein and adjacent channels on opposite sides of said compartment, a detachable cover for said compartment, and flanges depending from said cover and adapted to engage the channels in said comb body portion in sliding engagement therewith to permit sliding of said cover relative to said comb body portion, said flanges having chamfered ends to facilitate slidable removal of said cover from said body portion.
